DESIGN FOR A CORNER POST FOR A COT OR SIMILAR ARTICLE

Eugene D. Hallock, Buffalo, N. Y.

Application April 20, 1942, Serial No. 106,627

Term of patent 3½ years

To all whom it may concern:

Be it known that I, Eugene D. Hallock, a citizen of the United States, residing at Buffalo, in the county of Erie and State of New York, have invented a new, original, and ornamental Design for a Corner Post for a Cot or Similar Article, of which the following is a specification, reference being had to the accompanying drawing, forming part thereof.

Fig. 1 is a perspective view of a corner post for a cot or similar article, showing my new design;

Fig. 2 is a front elevational view; and
Fig. 3 is a rear elevational view thereof.

I claim:

The ornamental design for a corner post for a cot or similar article, as shown.

EUGENE D. HALLOCK.
